Elago USB C to USB Adapter 3.0 with Indicator LED for MacBook and More Type-C Devices (Silver), Amazon online, date first available Sep. 26, 2019, URL: <https://www.amazon.com/elago-Adapter-Indicator-MacBook-Devices/dp/B07YDHM296?th=1>, retrieved Sep. 24, 2020.*

Primary Examiner — Rebekah A Caruso(74) *Attorney, Agent, or Firm* — Paratus Law Group, PLLC(57) **CLAIM**

The ornamental design for a USB adapter, as shown and described.

DESCRIPTION

FIG. 1 is a front, top and left perspective view of a USB adapter showing claimed design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a front, bottom and right perspective view thereof; and,

FIG. 9 is a bottom, front and right perspective view thereof. The broken lines shown in FIGS. 1, 6, and 7 depict parts of the USB adapter, but form no part of the claimed design.
